UNITED STATES PATENT OFFICE.

FRANK H. CHAMBERLIN, OF CLEVELAND, OHIO.

SUPPORTING DEVICE.

SPECIFICATION forming part of Letters Patent No. 559,567, dated May 5, 1896.

Application filed July 8, 1895. Serial No. 555,243. (No model.)

To all whom it may concern:

Be it known that I, FRANK H. CHAMBERLIN, of Cleveland, in the county of Cuyahoga and State of Ohio, have invented certain new and useful Improvements in Supporting Devices; and I do hereby declare the following to be a full, clear, and exact description of the invention, such as will enable others skilled in the art to which it pertains to make and use the same.

My invention relates to improvements in supporting devices, more especially designed for holding a card, photograph, picture, or other small object upon a wall; and it consists in certain features of construction and combinations of parts hereinafter described, and pointed out in the claim.

In the accompanying drawings, Figure 1 exhibits a front view of a supporting device embodying my invention. Fig. 2 is a back view of the same; and Fig. 3 is a section on line 3 3, Figs. 1 and 2, looking in the direction of the arrow.

Referring to the drawings, 5 designates the body portion of a preferred construction of device embodying my invention, said body portion, upon its rear side, and centrally thereof, being provided with a rearwardly-projecting point 6 for the purpose of attaching the device to a wall, and the body portion, upon its forward side, is provided with a tongue or stiff member 7, projecting from the edge of the device and projecting inwardly over and arranged radially of the front side of the device. Member 7 possesses sufficient elasticity or springiness to render it capable

of pressing against the body portion of the device an article inserted between said member 7 and the forward side of the body portion of the device.

The body portion of the device is preferably made of two pieces of sheet metal, one, 8, of which pieces is arranged at the rear of the other, and point 6 is formed upon the rearward piece. Member 7 is formed upon the forward piece 9, and the latter is provided with any suitable number of arms 10, projecting from the edge of piece 9 at different points, respectively, and bent over the edge of and clenched upon the back side of the point-bearing piece.

What I claim is—

A supporting device of the character indicated, comprising two pieces of sheet metal 8 and 9 arranged the one 8 at the rear of the other, the rearward piece being provided with a rearwardly-projecting point and the forward piece being provided with means instrumental in supporting the article to be held or supported and being provided with any suitable number of arms 10 projecting from the edge of the piece and bent over the edge and clenched upon the back side of the point-bearing piece, substantially as shown, for the purpose specified.

In testimony whereof I sign this specification, in the presence of two witnesses, this 3d day of July, 1895.

FRANK H. CHAMBERLIN.

Witnesses:

C. H. DORE,
L. WARD HOOVER.
